(57) **CLAIM**

The ornamental design for a jewelry article, as shown and described.

DESCRIPTION

FIG. 1 is a front perspective view of a jewelry article showing our new design;

FIG. 2 is a front view of the jewelry article as shown in FIG. 1;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another front perspective view of the jewelry article as shown in FIG. 1, with unclaimed portions of the bow;

FIG. 9 is a front view of the jewelry article as shown in FIG. 8;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines shown in the drawings illustrate portions of the article that form no part of the claimed design.

1 Claim, 10 Drawing Sheets
